UNITED STATES PATENT OFFICE.

GEORGE W. GOSS AND CHARLES E. GOSS, OF BALTIMORE, OHIO.

CONVERTIBLE WAGON-BED.

1,266,582.

Specification of Letters Patent.

Patented May 21, 1918.

Application filed June 13, 1917. Serial No. 174,601.

To all whom it may concern:

Be it known that we, GEORGE W. Goss and CHARLES E. Goss, citizens of the United States, residing at Baltimore, in the county 5 of Fairfield and State of Ohio, have invented certain new and useful Improvements in Convertible Wagon-Beds, of which the following is a specification.

This invention relates to convertible 10 wagon beds designed for use particularly in connection with heavy hauling upon a farm. The wagon is so constructed that the bed thereof may be provided with high side and end boards to give considerable capacity 15 when it is desired to convey certain materials and also so that the side boards may be swung outwardly to a somewhere near horizontal position to give greatly increased width when it is desired to convey these 20 materials.

The main object of our invention resides in the provision of two sets of bracket members designed to coöperate with suitable side boards and arranged to be held locked in 25 either an upright or an outward position, as may be desired. In this connection, it is also an object of our invention to provide heel portions upon which the ends of the brackets may rest, these heel portions being 30 located outward from the side of a wagon and beyond the point of connection of the two brackets.

A further object of our invention also resides in a novel structure whereby the auxiliary side boards may be additionally braced in either of their applied positions.

The preferred embodiment of our invention is shown in the accompanying sheets of drawings, in which similar characters of 40 reference designate corresponding parts, and in which:

Figure 1 is a side view of our wagon showing the auxiliary side boards elevated,

Fig. 2 is an end view of our wagon showing the auxiliary side boards in their outward positions,

Fig. 3 is a view in perspective of one set of bracket members, showing the same in outward position,

Fig. 4 is a similar view showing the auxiliary bracket in an upright position, and,

Figs. 5 and 6 are detached perspective views of the two bracket members.

We have designated the wagon bed gen-

erally by the reference numeral 1, it being 55 understood that this wagon bed is suitably supported by wheels 2 and is provided with end boards 3. These end boards are preferably of a height equaling the height of the side boards when the auxiliary side 60 boards are applied and are in their upright positions. Short side boards 4 are also provided and preferably remain in their applied positions as shown in Figs. 1 and 2. Each of the side boards has bolted to it a plurality of suitable bracket members 5, the bolts passing through the flanges 6 and the portions 7 serving as braces to suitably strengthen the same. At their upper ends, these braces carry upwardly projecting 70 tongues 8, each provided with an aperture 9 to receive the locking pin. These braces are also provided with an outwardly extending heel portion 10 designed to serve as a base upon which either of the heel portions 75 11 or 12 of the auxiliary brackets 13 may rest. These auxiliary brackets 13 are also suitably bolted to auxiliary side boards 14 by means of the flanges 15. These auxiliary brackets are also suitably braced, as 80 shown at 16 and are provided with a pair of sockets 17 and 18 disposed at substantially right angles to each other and designed to properly fit the upstanding tongues 8. Each of the portions wherein the sockets 85 17 and 18 are located, is also provided with alining apertures 19 designed to coöperate with the apertures 9 through the medium of the pins 20, which latter are attached to the chains 21, to suitably hold the brackets in 90 position.

The operation of our device thus far described is as follows: After the wagon has been constructed and the two sets of side boards also constructed, the brackets 13 are 95 placed in a position so that the sockets 17 fit over the tongues 8. In this position, the auxiliary side boards 14 will stand in an upright position and the heel portions 11 will rest upon the heel portions 10 of the 100 auxiliary brackets 7. This structure makes for rigidity and is deemed to be particularly desirable. Should it be desired to have the auxiliary side boards in an outward position, their brackets are disengaged from the 105 main bracket 6 and the sockets 18 made to engage the tongues 8. In this position, the heel portions 12 engage the heel portions 10

and the brackets may be locked in position by applying the pins 20 through the apertures 19 and 9.

In order to additionally brace or hold the auxiliary side boards in position, we have provided ordinary link chains 22 which are secured to the auxiliary side boards at a point adjacent their upper edges, as is shown at 23. The end boards 3 each carry a pair of hooks 24, whose mouth portions extend upwardly and it is by means of these hooks that the chains may be dropped into their proper position and thus held. Thus, when the side boards are in the position shown in Fig. 2, the chains are first released and after the side boards have been swung outwardly, they are dropped into position to securely brace these side boards, as will be apparent. Similarly, when the side boards are in upright position, the chains are first removed and then again hooked into position to hold the auxiliary boards upright.

In Fig. 2, we have shown a slide bar 25, designed for use in assisting the user in changing positions of the auxiliary side boards. It will appear from Fig. 2 that it is necessary to disengage all of the bracket members before the sides may be swung to an upright position. To accomplish this, the slide bar 25, held in place by means of the bearings 26 is slid outwardly, say to the left, as is shown by dotted lines in Fig. 2. Before this, however, the side board has been lifted so that the slide bar 25 is in a position beneath the same. The auxiliary side board may then be lowered to rest upon this slide bar and its other end grasped and disengaged from the remaining brackets and then swung to a vertical position, it being understood that there is sufficient play between parts to allow this, whereupon it may be lowered to again seat itself over the tongues 8. After this, the operator may return to the end where the slide bar 25 is located and withdraw the same to lower the auxiliary side board and place it in its proper position. This same operation may be repeated on the other side by sliding the slide bar to the right.

From the foregoing description, it will be apparent that we have provided a wagon wherein the side boards may be moved to an upright or to an outward position. Novel means have been provided for holding these side boards in such position and in addition,

structure has been provided in the slide bar 25 for permitting the conversion by a single operator.

What we claim, is:

1. A convertible wagon bed comprising a bed body, short side boards forming a portion of said bed body, brackets rigidly secured to said short side boards, auxiliary side boards, auxiliary brackets on said auxiliary side boards, a substantially horizontal heel portion on each of one set of said brackets, a substantially horizontal and a substantially vertical heel portion on the co-operating end and the outside face of each of the other set of brackets, and means for mounting said sets of brackets together so that either of the horizontal or the vertical heel portions of the one set co-operates with the horizontal heel portion of the other set. 65

2. A convertible wagon bed comprising a bed body, short side boards forming a portion of said bed, brackets rigidly secured to said short side boards, auxiliary side boards, auxiliary brackets on said auxiliary side boards, a tongue on each of one set of brackets and a pair of sockets disposed at an angle to each other in each of the other set of brackets, said tongue fitting said sockets, a heel portion on one and a pair of heel portions on the other of said brackets located 80 outwardly beyond said tongue and sockets to be in engagement with each other, and means for connecting said two sets of brackets together in either an upright or outward position. 85

3. A convertible wagon bed comprising a bed body, short side boards and end boards forming a portion of said bed, auxiliary side boards, means for securing said two sets of side boards together in either an upright or outward position, and a bolt slidably carried by one of said end boards upon which said auxiliary side boards may rest temporarily while changing said auxiliary boards from one position to another, said bolt being slid- 95 able to project beyond either side of the wagon bed. 100

In testimony whereof we affix our signatures in presence of two witnesses.

GEORGE W. GOSS.
CHARLES E. GOSS.
